UNITED STATES PATENT OFFICE.

WILLIAM EDWARD WEBB, JR., OF LARCHMONT, NEW YORK.

NECKWEAR.

1,101,769.

Specification of Letters Patent. Patented June 30, 1914.

Application filed January 12, 1914. Serial No. 811,568.

To all whom it may concern:

Be it known that I, WILLIAM E. WEBB, Jr., a citizen of the United States, and resident of Larchmont, county of Westchester, and 5 State of New York, have invented certain new and useful Improvements in Neckwear, of which the following is a specification.

This invention relates to neckwear and it is adapted to various forms of ties, for instance, four-in-hands, ascots, etc.

The invention is especially designed for use on neckties made up of woven, knit or other fabric cut to the proper shape and folded to make the complete tie, a suitable 15 lining material being placed between the folds of the necktie material, said lining running throughout the neckband portion and the knot-tying portions of the tie.

The invention is especially designed for 20 neckties adapted to be worn with turned-down or double-fold collars. As is well known it is many times extremely difficult to adjust a necktie between the folds of a double-fold collar and frequently considerable strain is brought on the necktie in shifting it to its proper position for tying. This 25 strain frequently results in the folding of the lining within the tie. Heretofore this lining has not been stitched to the material 30 forming the tie except throughout the narrow neckband portion thereof.

A necktie made up in accordance with the invention described herein will be provided with a lining substantially conforming to the 35 shape of the tie, said lining being stitched to the back fold of the tie along the longitudinal edges of the tie and the lining. By this means the entire tie will be reinforced and strengthened not only at the neckband portion but through the knot-forming portions 40 thereof. The said tie will also be reinforced throughout the neckband portion and the knot-forming portions by a reinforcing strip stitched to the back fold of the tie and to the lining, said stitches extending through the 45 reinforcing strip, the back fold of the tie and the lining. Throughout the neckband portion of the tie the stitches securing the lining and the reinforcing strip in position will extend through the face of the tie so that said 50 neckband portion will be greatly strengthened and will be held flat.

In the drawing, Figure 1 is a face view of a necktie of the four-in-hand type; Fig. 2

a rear view thereof; Fig. 3 a transverse sectional view on the line III—III of Fig. 2; and Fig. 4 a detail view of a portion of a tie showing the reinforcing strip omitted, the lining serving the purpose of a reinforcing and strengthening means for the tie.

Referring to the various parts by numerals, 1 designates the body portion of the necktie which is cut and folded so that a longitudinally extending seam 2 is formed along the center of the back of the tie. This 65 seam extends from the ends of the neckband portion 3 outwardly to the ends of the knot-tying portions 4, the two edges of the necktie fabric being stitched together to form said seam, if that be desirable. The tie is 70 lined throughout the neckband portion and the knot-tying portions by a suitable lining material 5, said lining being shaped substantially to conform to the shape of the tie. The seam or joint 2 between the edges of the 75 necktie material is covered throughout its entire length by a reinforcing strip 6, said strip being of any suitable width and of any suitable smooth, closely woven or non-friction material. This reinforcing strip is 80 stitched by lines of stitches 7 to the lining, shown clearly in Fig. 3. These lines of stitches pass through the reinforcing strip, the back fold of the tie and the lining but do not pass through the face or front fold of 85 the tie so that they do not appear on the face of the tie.

The object of securing the lining throughout its length to the reinforcing strip is to materially strengthen the tie and to prevent the seam 2 being opened by any strain placed on the tie, and also to maintain the lining flat within the tie and throughout the length of the lining. The lining 5 is stitched along its longitudinal edges and 90 throughout its length to the back fold of the tie independently of the stitches which secure the reinforcing strip to the lining. By this means the entire tie is strengthened and the lining is absolutely prevented from 95 curling or stretching independently of the necktie. It is manifest that if desired the seam protecting and reinforcing strip 6 may be omitted, as shown in Fig. 4, the lining alone serving as beneficial means for 100 strengthening the tie and preventing its longitudinal elongation.

In ties heretofore made the lining is at-

tached to the body of the tie only at the neckband portion thereof, that portion of the lining within the knot-tying portions of the tie being free to turn and fold independently of the outer folds of the tie. With the arrangement described herein the lining is permanently attached to the rear fold of the tie along the two longitudinal edges of the reinforcing strip so that it is impossible for the tie to become twisted or folded. This construction also prevents the lining being pulled or stretched longitudinally. This is a frequent cause of dissatisfaction with lined ties. The lining will frequently stretch and become exposed at the ends of the tie. The stretching of the lining also reduces its width and tends to coil or fold it longitudinally within the tie. All of these objections are avoided by my invention. It is essential that the lining and the reinforcing strip be secured to the rear folds of the tie by means which does not pass through the face of the tie at the knot-tying portions thereof.

In some forms of neckties the lining extends only through the knot-tying portions thereof, and does not extend through the narrow neckband portion. In ties of this construction made in accordance with my invention the two sections of the lining will be secured to the back fold or portion of the tie. The reinforcing strip is then secured to the back fold or portion of the tie and extends throughout the neckband portion and the knot-tying portions, said reinforcing strip being secured to the lining throughout the knot-tying portions of the tie and through both folds of the tie at the neckband portion thereof. It will, of course, be understood that the stitches securing the lining to the back fold of the tie, and the stitches securing the reinforcing strip to the back fold or portion of the tie throughout the knot-tying portions thereof do not extend through the face or front fold of the tie. It will, of course, be understood that this invention is applicable to neckties whether they be woven, knitted or crocheted to the proper shape, and whether or not the same in the folded tie is at the middle of the back fold or portion thereof, or any other place.

What I claim is:

1. A necktie formed of suitable fabric folded and shaped in a flat tubular form and embodying a narrow neckband portion and wider knot-forming portions at the ends of the neckband portion, the edges of the folded fabric being at the middle of the back fold of the tie, a lining extending through the knot-forming portions and the neckband portion, a reinforcing strip on the back fold of the tie and covering the edges of the folded necktie fabric and extending throughout the neckband portion and the knot-forming portions, said strip being substantially equal in width to the neckband portion, and lines of stitches extending along the longitudinal edges of said reinforcing strip, said stitches attaching the lining to the back fold only of the tie throughout the knot-forming portions on both sides of the joint between the edges of the folded necktie fabric, whereby said stitches will not appear on the face of the tie, and the lining will be secured near its longitudinal edges and throughout its length to the back fold only of the tie. 75

2. A necktie formed of suitable fabric folded and shaped in tubular form and embodying a narrow neckband portion and outwardly flaring knot-forming portions at the ends of the neckband portion, the edges of the folded fabric being at the middle of the back fold of the tie, a lining extending through the knot-forming portions, said lining being of substantially the same shape as the necktie, and lines of stitches extending along the longitudinal edges of the lining and near the longitudinal edges of the necktie, said stitches attaching the lining to the back fold only of the tie throughout the entire length of said lining and on both sides of the joint between the edges of the folded fabric, whereby said stitches will not appear on the face of the tie. 85 90

In testimony whereof I hereunto affix my signature in the presence of two witnesses. 95

WILLIAM EDWARD WEBB, Jr.
